BOWSIGHT

William A. Ambrasiatis, 15350 Carfax,
Bellflower, Calif. 90706
Filed June 28, 1965, Ser. No. 467,479
3 Claims. (Cl. 33—46)

This invention relates to an adjustable bowsight and more particularly to a bowsight using a reflecting surface for maintaining alignment of an arrow for striking an object.

An archer is confronted with the problem of pulling a bowstring a preferred distance and releasing it at an exact time. Assuming that all other factors remain the same, if an archer is able to pull and release according to a definite and repeatable pattern, his accuracy remains the same. When an archer has initially determined a proper draw and release, that accuracy would remain fixed and would result in a high accuracy arrow strikes.

However, in most cases, the archer is not able to maintain a fixed pattern. Under usual shooting conditions, the archer cannot see the arrow and has no way of determining how far he has pulled it. Even if he could see the arrow, he could not accurately determine the length of pull due to the fact that he is looking at the arrow from behind and at a downward angle.

Certain mechanical devices have been provided, called draw checks, such as a button glued to the string that should touch the same spot on the archer's face (anchor point) with each draw. The devices aid the archer but do not enable him to see the draw of his arrow. Arrow draw is particularly important over a long shooting interval, of, for example, 100 arrows or more. An archer tends to permit his arrow to creep forward due to tiredness with the result that the shots become progressively lower.

The invention described herein overcomes, to a large extent, the problems described above by providing a means permitting an archer to observe arrow draw and to improve shooting accuracy by using an improved means for sighting his bow on an object such as a target.

Briefly, the inventive bow sight comprises reflection means such as a right angle prism having a reflective hypotenuse surface such as a mirrored surface for reflecting the arrow image to the eye of the archer so that the arrow tip is aligned on the bullseye of a target or other object. Adjusting means are provided for calibrating the bowsight for accuracy under various conditions. The adjusting means includes means for adjusting arrow drift in a horizontal plane and for target distance according to an individual archer's shooting characteristics.

Therefore, it is an object of this invention to provide an improved bowsight for permitting the archer observation of his arrow draw;

It is a further object of this invention to provide a bowsight using a reflecting surface for permitting an archer to observe the draw of his arrow;

A still further object of this invention is to provide an improved bowsight for maintaining a repeatable shooting pattern under various shooting conditions;

A still further object of this invention is to provide an improved bowsight which can be pre-calibrated according to particular shooting conditions.

These and other objects of this invention will become

2

more apparent with the following description taken in connection with the accompanying drawings of which:

FIG. 1 is a side view embodiment of the bowsight affixed to a drawn bow.

5 FIG. 2 is a partial section taken along lines 2—2 of FIG. 1 showing the rear view of the sight affixed to a bow including the end view of an arrow.

FIG. 3 is a left side partial section view taken along lines 3—3 of FIG. 2 showing the bowsight affixed to a bow.

10 FIG. 4 is a front view of the sight removed from the bow taken along lines 4—4 of FIG. 1.

FIG. 5 is a front side view of the sight in elevation.

15 FIG. 6 is a rear view of the bowsight showing the reflective means at an angular position.

Referring now to FIG. 1, wherein is shown bowsight 1 attached to the mid-section of bow 2 at a grooved area formed or cut in the body near its center. Also shown therein is arrow 3 supported by arrow rest 4. The arrow is in a drawn position with its feather tip or slotted end contacting string 5. The string, pulled tight, provides the force for driving the arrow through the air towards an object when released.

20 Referring now to FIG. 2, wherein is shown sight bar 20 joined to horizontal sliding bars or rods 21 and 22. For clarification, rods 21 and 22 are assumed to extend along a horizontal X axis direction.

25 Lock screw 23 and 46 (see FIG. 3) are provided for securing the sight bar at a particular horizontal position.

30 Also shown in FIG. 2 is a reflecting means 24 enclosed and mounted inside holder means 25. For the embodiment shown, the reflecting means is a prism having a mirrored surface as its hypotenuse side, that is, side 26 (see FIG. 3). It should be understood that the other reflecting means are also within the scope of the invention, such as a mirror placed at a 45° angle, with respect to a horizontal Z axis taken along rod 43 (see FIG. 5). Also, a polished metal surface may be used.

35 Ball alignment means 27 and 27' such as metal spheres are affixed to the holder means, for example, by soldering, and are used to align the arrow on a target. Target bullseye 28 is aligned along the bottom portion of the prism. The target may be various distances from the bow and is reproduced in part for illustration of the alignment.

40 The striking end of the arrow 4, tip 29 (see FIG. 3), is reflected by surface 26 so that the tip image is covered or aligned with ball alignment means 27. The ball alignment means is centered in target 28. For a left-handed archer, the reflecting means may be removed and inserted at the opposite side of the sight housing via the opposite end of the threaded sleeve 44 (see FIG. 5) and adjusted for alignment.

45 FIG. 2 also illustrates sight housing 30 which moves vertically with respect to the bow. Openings 31 and 32 are provided in the housing for movement of horizontal rods 21 and 22. Openings 33 and 34 are provided for vertical rods 35 and 36. The vertical rods provide the sight with a capability of adjustment along a vertical axis with respect to the bow. For purposes of the description, the vertical axis is assumed to be in a Y direction.

50 Locking screws 37 and 38 (see FIG. 4) are provided for locking in sight housing in place in a selected vertical position. The vertical rods terminate and are joined at plates by means 39 and 40 (see FIG. 3).

55 65 In a preferred embodiment, the plate means, sight

housing and sight bar are comprised of aluminum with the remaining portions excluding the reflector means, being comprised of stainless steel. The assembly may be chrome-plated and dyed black or other colors. In other embodiments, the entire assembly may be comprised of stainless steel, aluminum, or a plastic material, or any combination thereof. The reflecting means in one embodiment is comprised of an optical glass prism having a mirrored surface which may, for example, be painted on the hypotenuse side of the glass prism.

It should be understood that the scope of the invention is not limited to the particular materials and processes described in connection with the illustrated embodiments and that the invention includes or substitutes and changes that obvious to those skilled in the art.

Referring now to FIG. 3, wherein the sight is shown from the side. As shown in FIG. 3, plates 39 and 40 are L shaped. Vertical rods 35 and 36 are joined to one portion of the plates by means such as welding. The other portion joins the sight to the bow.

The sight is secured to the bow by screw means 41 and 42 which attach the plate to the bow through openings provided in the plates.

Horizontal rod means 43, is shown joined to sight bar 20 through threaded sleeve portion 44 which is connected to the sight bar, for example, by welding. For purposes of description, movement of rod means 43 is assumed to be along a horizontal Z axis direction and angular about said Z axis. Rod 43 is threaded for mating with the sleeve. Threaded lock nut 45 mates with rod 43 and sleeve 44 for locking the rod at a particular horizontal position along the Z axis. The threaded nut may be loosened also to permit adjustment of the reflection means to a desired angular position about the Z axis.

The horizontal X and Z position adjust means, the vertical adjust means, and the angular adjustment means gives the sight 3 degrees of freedom in addition to the angular adjustment about the Z axis.

Referring now to FIG. 4, the sight is illustrated from a rear view. Lock screws 23 and 46, for locking the sight bar in place along its horizontal X axis, are more clearly illustrated as are lock screws 37 and 38 for locking the sight bar in place along its vertical axis. Bars 35 and 36 are also more clearly illustrated. The end position of horizontal rod 43 including the sight bar and lock nut 45 are also shown in a different view.

Referring now to FIG. 5, the horizontal rod 43 and other portions of the sight are shown in perspective. The reflecting means 24 can be moved along its horizontal Z axis forward and backward and along its horizontal X axis in and out of the sight housing 30. An archer views the arrow image along the horizontal Z axis looking into reflecting means 24.

It should also be understood that sight bar 20 could be threaded so that rod 43 would mate with the threaded portion, and sleeve 44 could be eliminated. Other embodiments are also possible.

Briefly, the sight operates to improve the archer's shooting accuracy. If it is desired to raise the arrow's trajectory, the reflecting means is lowered by loosening the locking screws 37 and 38 and manually sliding the sight housing along rods 35 and 36. The exact height is determined empirically by the archer. The arrow trajectory is raised if the reflecting means is lowered and the trajectory lowered if the sight is raised.

It may be desirable to adjust the sight for arrow drift, either right or left. This adjustment is achieved by loosening lock screws 23 and 46 and sliding rods 21 and 22 through the sight housing until the drift of the arrow, due for example to wind, has been compensated for. As before, the archer empirically determines the exact X axis horizontal position. If the arrows are drifting to the left, the reflecting means is moved to the left which forces the archer to move the bow to the right

to place the sight on target. The reverse is true for right arrow drift. After the exact horizontal position is selected, screws 23 and 46 are locked. Lock nut 45 is loosened to permit angular rotation of the reflection means so that the arrow image can be seen on the reflecting surface. For example, in FIG. 6, reflecting means 24 including the holder and other portions thereof, such as the alignment means has been rotated approximately 51° to permit the archer to view the arrow tip from that particular horizontal position. 51° rotation is only required for extreme cases to correct for arrow drift in a horizontal plane. Ordinarily, rotation of less than 15° is required to maintain a tip image in the reflecting means.

After the horizontal X axis and vertical positions are selected, lock nut 45 is loosened so that each archer can adjust the reflecting means along its Z axis (horizontal) to place the tip of the arrow exactly on target as viewed through the reflecting surface. After the exact position is selected for a particular distance of arrow travel, the nut is locked.

Usually, an archer will shoot from 6 to 12 arrows at a target to establish a group or pattern. The archer retrieves his arrows, adjusts his bowsight and continues shooting until he is satisfied with the pattern he obtains. For that particular distance the archer places a mark on a piece of tape (not shown) on the side of the bow indicating the sight setting. Ordinarily, the vertical setting only is marked down because horizontal position is dependent on wind conditions for a particular day and location.

After a sight has been calibrated for a particular distance, the archer needs only to properly align the target bullseye, ball alignment and arrow tip within the reflecting means in order to obtain an accurate shot.

Although the invention has been described and illustrated in detail, it is to be understood that the same is by way of illustration and example only and is not to be taken by way of limitation, the spirit and scope of this invention being limited only by the terms of the appended claims.

I claim:

1. In combination, a bow and bowsight secured to said bow, said bowsight comprising reflection means for reflecting the image of an arrow tip for viewing by an archer, including means for aligning said tip on a target, said means for aligning being connected to said reflection means, and longitudinally movable and rotatable rod means for adjusting said reflection means and said means for alignment along a Z axis and 360° about said Z axis, said rod means being connected to said reflection means, and sleeve means for receiving said rod means, said rod means being rotatably engaged with said sleeve means and, means for holding said rod means at a selected location along said Z axis whereby said reflecting means is held at a selected angle about said Z axis, and means for adjusting said reflection means along an X axis and means for adjusting said reflection means along a Y axis, said X axis adjusting means including a bar member connected to said sleeve means.
2. The combination as recited in claim 1, wherein said both means for adjusting have a housing means having vertical and horizontal openings, and said Y axis adjusting means includes Y axis rod means for slidably engaging said housing in said vertical openings, said Y axis rod means being secured to said bow, and, said X axis adjusting means includes X axis rod means for slideably engaging said housing in said horizontal

openings, said bar member being also connected to said X axis rod means.

3. The combination is recited in claim 1 wherein said rod means comprises a threaded member and said sleeve means comprises a first threaded sleeve member which mates with said threaded rod means, and said means for holding comprises a second threaded sleeve member which mates with said threading bar member for securing said rod means against said first threaded sleeve member.
